(57) **CLAIM**

The ornamental design for an outer covering for a percussive high frequency chest wall oscillation system, as shown and described.

DESCRIPTION

FIG. 1 is a front perspective view of an outer covering for a percussive high frequency chest wall oscillation system in accordance with the present design;

FIG. 2 is a front elevation view thereof;

FIG. 3 is a rear elevation view thereof;

FIG. 4 is right side elevation view thereof;

FIG. 5 is a left side elevation view thereof;

FIG. 6 is a top plan view thereof; and,

FIG. 7 is a bottom plan view thereof.

The broken lines showing the remainder of the outer covering for a percussive high frequency chest wall oscillation system are directed to environment. None of the broken lines form a part of the claimed design.
